SHOE GUARD

Roy U. Gilreath, 5722 Kingston Pike, Knoxville 19, Tenn., and Archie R. Settemire, 421 Woodlawn Pike, Knoxville 20, Tenn.

Filed Mar. 21, 1962, Ser. No. 181,301

8 Claims. (Cl. 36—72)

This invention relates to a foot guard particularly designed to protect the foot from injury when working with machines such as a power lawn mower.

It is an object of the invention to provide a guard which may be easily applied or removed from the shoe and when applied will prevent the shoe from coming in contact with the rotary blade of a lawn mower.

A further object of the invention resides in forming the guard from a single length of wire bent to provide an upstanding fender section at the front end of the toe portion of a shoe which extends upwardly above the toe portion, a bracing section extending downwardly from the upper end of the fender section into engagement with the top of the toe portion and resilient gripping jaws extending rearwardly from the lower end of the fender section for releasably gripping the sides of the toe portion to hold the guard in place.

Another object of the invention resides in providing a foot guard which is simple and durable in construction, reliable and efficient in use and inexpensive to manufacture.

Other objects and advantages of the invention will be apparent during the course of the following description.

In the accompanying drawing forming a part of this specification and in which like numerals are employed to designate like parts throughout the same,

FIG. 1 is an illustrative view of a power mower and operator showing the foot guard applied to the shoe of the operator.

FIG. 2 is a top plan view of the guard with the foot shown in dotted lines,

FIG. 3 is a section taken on lines 3—3 of FIG. 2, and,

FIG. 4 is a perspective view of the guard with the shoe shown in dotted lines.

In the drawing wherein for the purpose of illustration a preferred form of the invention is shown, the letter A denotes generally the foot guard which is formed from a single strand of resilient wire of fairly heavy gauge. The length of wire is bent intermediate its length to form spaced parallel strands 5 and 6 having horizontal portions forming a base member adapted to extend longitudinally of the sole of a shoe with the free ends bent outwardly and curved upwardly to form hooks 7 and 8 adapted to resiliently engage over the sides of the shoe toe, with one of the hooks disposed further back on the toe portion than the other hook, as clearly shown in FIG. 2. The hooks terminate in loops 9 and 10 and if desired an elastic band or spring 11 may be connected to the loops across the toe of the shoe to firmly secure the hooks in gripping engagement with the shoe. The strands 5 and 6 are bent to provide vertical portions 12 and 13 to form a vertical member extending at right angles to the horizontal portion upwardly in front of the shoe toe to a height above the top of the toe portion. Also the strands are bent to form inclined portions 14 and 15 extending down from the upper ends of the vertical portions and then bent to provide upper horizontal portions 16 and 17 to form a brace member for engaging the top of the shoe toe with the loop end 18 of the bent wire bent to project upwardly from the top of the toe portion to provide a finger grip.

In use, the guard is slipped over the toe of the shoe until the vertical portions 12 and 13 are in contact with

2

the toe portion and is held in position by the hooks 7 and 8 which resiliently grip opposite sides of the shoe toe. The inclined portions 14 and 15, and upper horizontal portions 16 and 17 which are in contact with the top of the toe portion serve to brace the upper ends of the vertical portions. The loop end 18 serves as a finger grip to facilitate the application and removal of the guard from the shoe. Thus it is seen that with the guard applied to the shoe the spaced vertical portions of the wire will serve as a fender to prevent the foot from contacting the blade of a power mower should the foot slip on the ground while pushing the mower. Owing to the resiliency of the guard it may be easily attached to shoes of various sizes and shape and being of light construction will not be objectionable due to the added weight to the foot. Also the portions of the wire which extend along the bottom of the shoe sole serve to grip the ground under pressure of the foot and thus act to prevent the foot from slipping.

15 It is to be understood that the form of the invention herein shown and described is a preferred example of the same and changes in the shape, size and arrangement of the parts may be made without departing from the spirit of the invention.

20 Having thus described our invention, we claim:

1. A foot guard attachment for a shoe comprising a base member extending longitudinally of the foot portion of the shoe sole, a vertical member extending upwardly from the base member in front of the toe portion of the shoe to a point above the upper surface of the toe portion, and a resilient brace member inclined downwardly from the upper end of the vertical member into contact with the upper surface of the toe portion.

2. A foot guard attachment as described in claim 1 including hooks carried by the base member for engagement with the sides of the toe portion for securing the base member to the shoe sole.

3. A foot guard attachment as described in claim 1 including hooks carried by said base member adapted to engage over the sides of the toe portion of the shoe and resilient means extending across the toe portion connected to said hooks.

4. A foot guard attachment for a shoe comprising parallel strands of resilient wire having horizontal portions for engagement with the sole of the shoe, vertical portions bent at right angles to said horizontal portions extending upwardly in front and above the toe portion of the shoe, and bracing portions inclined downwardly from the upper ends of the vertical portions into engagement with the top surface of the toe portion.

5. A foot guard attachment for a shoe comprising a single strand of resilient wire bent intermediate its ends to form parallel strands with horizontal portions for engagement with the sole of the shoe, vertical portions bent upwardly from the horizontal portions in front of the toe portion of the shoe and extending above the toe portion and bracing portions inclined downwardly from the upper ends of the vertical portions into engagement with the top surface of the toe portion.

6. A foot guard attachment as described in claim 5 wherein the horizontal portions are provided with hooks to resiliently engage the sides of the toe portion.

7. A foot guard attachment for a shoe comprising a single strand of resilient wire bent intermediate its ends to form spaced parallel strands, said strands being bent to form upper and lower horizontal portions for resilient engagement with the top and bottom surfaces of the toe portion of the shoe and vertical portions extending vertically in front of the toe portion and connecting the upper and lower horizontal portions, said lower horizontal portions having their free ends bent outwardly and

upwardly to form hooks for engagement with the sides of the toe portion.

8. A foot guard attachment as described in claim 7 including resilient means extending across the toe portion connecting the hooks of said lower horizontal portions. 5
